(57) **CLAIM**

The ornamental design for a golf ball, as shown and described.

DESCRIPTION

FIG. 1 is a front elevation view of a golf ball, showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is right side elevation view thereof; and,

FIG. 7 is a top, left side perspective view thereof.

The broken lines shown in the figures depict portions of the golf ball that form no part of the claimed design.

1 Claim, 7 Drawing Sheets
